Thomas Gilpin
Filed Patent

The schedule referred to in this Filed Patent and making part of the same containing a description in the words of the said Thomas Gilpin himself of his improvement in machinery for finishing paper.

In compliance with the provisions of the Patent law I do describe my process, invention and discovery, of the art of ironing and finishing paper by a rolling process of machinery, to be in manner as follows to wit: I construct a roller to be made of paper compressed upon an iron shaft and then turned on the surface perfectly smooth and true in the same manner as those are made which are used for the calendering of cloth and cotton goods in the usual manner as well known, and I suspend the same in a frame usually made of iron with adjusting screws over the journals to press down the same and regulate the pressure as required. and I also provide an iron cylinder perfectly smooth on the outside but so large as to afford room to be hollow in the inside for the admission of heat conveniently; say from four to eight inches diameter and this said hollow iron cylinder is to be suspended in the same frame as the aforesaid paper roller and may be put immediately below the same, so that by the pressure of the screws the paper roller may be let down upon the same, and then when a power is applied upon a pulley in the well known usual manner either from a revolving shaft or cog wheel to the said hollow cylinder or paper roller as convenience may dictate the two rollers are to be brought into contact and well revolve together. Heat may then be introduced into the iron roller by iron or other heat as by steam, the paper may then be passed between the two rollers and be pressed and to obtain this pressure by the said process consists my said art or invention. This done that

sure as well as the skill of managing the same is to be left to the further experience of the workman. I have also invented another machine to effect the same purpose of rolling paper, by using two paper rollers in a similar frame to the above, to move together in contact with each other, so as to admit the paper to pass between them, and in this frame I either use the two paper rollers together, or I use them with an iron roller between them, as may be most eligible - but the process I consider as analogous to the preceding. I have found it necessary also to add a useful instrument to the above invention for the purpose of securing the paper, as it is passed between the said rollers from injury, by creasing or running unevenly. This instrument I call a conductor. It may be made in a variety of forms, and such an instrument cannot well be done without in this application and process. The form I have used at this is by having a flat board suspended horizontally upon ^{two} wheels with two wheels on each side upon which the paper may be laid. I have then an open frame made to surround the said board. I suspend the same on the two sides on pivots. The one end or side of the open frame next to the rollers rests upon the said board and the other end or side comes underneath the said board so that it may be pressed up to it by the hand. The end next the rollers will then come down upon the board and the sheet of paper when laid upon the board is to be shoved or pushed forward upon it but under the end of the open frame which is above the board and by which it may be pressed and gripped as by a pair of tongs and kept smooth as it is drawn forward from the conductor unto the rollers, - The end of the open frame head being surrounded with a wooden cloth - the effect of squeezing or pressing, the paper firmly throughout the whole sheet, so that it may be delivered in an even manner and the rollers by any

process is part of my discovery, as it has never been done in any manner, — and (I describe the above as one way) I have adopted to effect it: it may become also by pressing a straight edge or cushion up to one of the rollers and passing the sheet of paper between the straight edge or cushion, so as to grip the paper against the roller in order to pass it evenly, into the action at the contact of the rollers. Another part of my invention consists in fixing a permanent iron bar or rod opposite to the contact or conjunction of the two rollers so that accidents may be prevented by things going into them or persons being caught and hurt by them. The said bar to be connected to the standard or sides of the iron frame on which the rollers are suspended.
